BROILER UNIT

Mary I. Williams, Parma, Ohio

Application May 17, 1949, Serial No. 2,710

Term of patent 14 years

(Cl. D81—10)

To all whom it may concern:

Be it known that I, Mary I. Williams, a citizen of the United States, residing in Parma, in the county of Cuyahoga and the State of Ohio, have invented a new, original, and ornamental Design for a Broiler Unit, of which the following is a specification, reference being had to the accompanying drawing, forming a part thereof.

In the drawing:

I claim:

The ornamental design for a broiler unit, substantially as shown.

MARY I. WILLIAMS.
